ATTORNEY

UNITED STATES PATENT OFFICE.

CLARENCE A. CRACRAFT, OF PEABODY, KANSAS.

SHAFT CONSTRUCTION.

Application filed April 5, 1924, Serial No. 704,486. Renewed September 15, 1926.

My present invention pertains to shaft construction and has for its object to provide an improved shaft construction of such character that the loss of a shaft on account of a flat side will be averted, the formation of a flat side being provided for by the employment and adjustment of blade sections.

To the attainment of the foregoing, the invention consists in the improvement as hereinafter described and definitely claimed.

In the accompanying drawings, forming part of this specification:—

Figure 1 is an elevation of a portion of a crank shaft constructed in accordance with my invention.

Figure 2 is a cross-section on line 2—2 of Figure 1, showing my improvement.

Figure 3 is a section on line 3—3 of Figure 1.

Similar numerals of reference designate corresponding parts in all of the views of the drawings.

In accordance with my invention the body or major portion 1 of the shaft is provided with an end 2 of general square form in cross-section with rounded corners 2a which end 2 can be of any length desired, according to the bearing in which it is disposed.

Grouped about the square end 2 and opposed to the four sides thereof are blade sections 3 which are flat at their inner sides and convex at their outer sides as illustrated so that when the blade sections 3 are initially arranged on the body or major portion 1, the end of the shaft will be as appears in Figure 2. The rounded corners of the shaft body 1 may be and preferably are in conformity with the convex sides of the blade sections 3 and render it feasible to make the said sections reasonably thin.

The body 2 is provided with dowel pins 4 to enter sockets 5 in the sections 3 for the purpose of holding the sections on the body; and it will also be noticed that the sections 3 are recessed at 6 for the interposition of a prying instrument in the displacement of the blade sections.

By virtue of the construction described a new shaft is not needed in the event of a flat side being formed; nor will it be necessary to true a shaft in such event. On the other hand all that is necessary is to remove the blade sections and replace each on the side in advance of its previous side until said operation has been performed four times, when the original blade sections will be replaced with a new set of sections and the shaft will be rendered as good as new.

Manifestly my improvement is applicable to any shaft that is liable to become flat.

I have entered into a detail description of the construction and relative arrangement of the parts embraced in the present and preferred embodiment of my invention in order to impart a full, clear and exact understanding of the said embodiment. I do not desire, however, to be understood as confining myself to the specific construction and relative arrangement of parts inasmuch as in the future practice of the invention various changes and modifications may be made such as fall within the scope of my invention as defined in my appended claim.

Having described my invention, what I claim and desire to secure by Letters-Patent, is:—

In a crank shaft construction, the combination of a body having a portion of angular form in cross-section blade sections flat at their inner sides and convex at their outer sides and opposed to the sides of the portion and capable of being shiftable about the said portion in the event of one becoming flat on its convex side, and dowel pins retaining the blade sections in working position on the body portion, the said portion of the body being square in cross-section with rounded corners, and the said blade sections having recesses opposite the sides of the body portion.

In testimony whereof I affix my signature.

CLARENCE A. CRACRAFT.
